UNITED STATES PATENT OFFICE.

HARVEY S. PARK, OF CHICAGO, ILLINOIS, ASSIGNOR TO ALBERT H. LOEB,
OF SAME PLACE.

FLUID-PRESSURE BRAKE.

SPECIFICATION forming part of Letters Patent No. 555,877, dated March 3, 1896.

Application filed September 30, 1895. Serial No. 564,116. (No model.)

To all whom it may concern:

Be it known that I, HARVEY S. PARK, a citizen of the United States, and a resident of the city of Chicago, in the county of Cook and State of Illinois, have invented certain new and useful Improvements in Fluid-Pressure Brakes, of which the following is a specification.

The object of my invention is to provide an automatic brake for railways which shall be simple in construction and positive and reliable in action; and my invention consists in the features and details herein described.

In the drawings, Figure 1 is a longitudinal view of the apparatus on line 1 of Fig. 2; Fig. 2, a cross-section on line 2 of Fig. 1. Fig. 3 is a view of the emergency-valve of the apparatus in elevation and showing the rear or inner side of the valve; Fig. 4, a sectional view of the emergency-valve and a part of the valve-casing, showing ports and passages for balancing the valve and drawn on line 4 of Fig. 2. Fig. 5 is a longitudinal view of the apparatus, the parts shown in dotted lines being on line 5 of Fig. 2 and the parts shown in full lines on line 5^a of Fig. 2 and showing the parts in position for making a service stop. Fig. 6 is a cross-section on line 6 of Fig. 5. Fig. 7 is a face view of the emergency-valve, showing the ports and passages located thereon. Fig. 8 is a view of the seat of the emergency-valve, showing the ports and passages located therein. Fig. 9 is a longitudinal view of the apparatus on line 9 of Fig. 6, showing the position of the parts in making an emergency stop. Fig. 10 is a view showing a spring that is fixed to the emergency-valve to hold it properly to its seat; and Fig. 11 is a view on line 11 of Fig. 6, showing the ports and passages leading from chamber F to the atmosphere.

In the drawings, A is a wall or casing forming a chest or chamber in which the device actuates, and A' a bushing fitted to the casing and forming an air-tight lining for the casing. The chamber C is formed by the casing A, in which the device operates, which chamber is of a cylindrical form, its upper part being smaller than its lower part. A by-port a is formed in the bushing A', which permits the air to pass the piston B when the pis-

ton is in its normal position, whereby the auxiliary reservoir is fed with air from the train-pipe.

B is a piston working and operating in the chamber C and actuating the emergency-valve D by means of the stem B', which extends to and into the upper part of chamber C. The piston actuates the emergency-valve on its downward move by a head on its upper end abutting arms that extend from the rear portion of the valve and across the chamber C, and it actuates the valve on its upward move by a shoulder on its lower end abutting arms that extend from the rear and lower part of the valve across the chamber C. These arms cross the chamber C and operate in a channel or groove cut in the bushing A and form a guide for the emergency-valve.

The valve D is the emergency-valve of the device and is balanced as to the ports and passages leading from the train-pipe to the brake-cylinder, by reason of having the air in these ports and passages, governed by the valve, to be the same pressure per square inch as the pressure on the opposite side of the valve, thereby enabling the valve to be moved or actuated with a very small pull. This valve is provided with a recess d, which connects the ports and passages leading from the train-pipe to the brake-cylinder when the valve is making its full travel, and forms a communication through which the air flows from the train-pipe to the brake-cylinder. In the emergency-valve is a recess d', which, when the valve is in its normal position, connects the passage or port e⁴ leading from chamber C to the brake-cylinder with the passage or port e⁵ leading from the chamber C to the atmosphere, and forming an open way from the brake-cylinder to the atmosphere. In the valve D is also a recess d², which on the valve's full travel connects with port or passage e⁶ located in the bushing A' leading to and connecting with passage e⁵ with the passage g', which leads to chamber F. By means of these ports and passages the emergency-valve forms an open way from chamber F to the atmosphere. A slot or passage d³ is provided in the emergency-valve and when the valve is in its normal position and while making its first travel the slot connects

with the port or passage g formed in the bushing A' , which latter passage connects with the recess d also while the valve is in its normal position and making its first travel. A chamber E is preferably formed on and integral with the emergency-valve, and is provided with a piston E' , having a stem E^2 , carries a valve E^3 , which is the service-valve of the device. A screw-plug E^4 is fitted into the upper part of the chamber E , closing its upper end and forming a seat for the service-valve, and a passage e' is formed in the plug and leads to a recess d^4 in the emergency-valve. A passage e is formed in the emergency-valve, the upper end or opening connecting with the lower part of chamber E and its lower end opening in the face of the emergency-valve. While the emergency-valve is in normal position and making its first travel this passage connects with the port or passage G , leading from the train-pipe through the passage N . Through the passage G and e the train-pipe air is fed to the chamber E below the piston E' . An opening or passage e^2 is formed in the wall of chamber E admitting auxiliary-reservoir air to the chamber E above the piston E' .

A casing L is fixed to the lower end of casing A , closing its lower end and forming the chamber L' , in which is located and operated the stem M , whose upper end passes through the wall L and terminates in the chamber C . This stem has a shoulder that abuts the wall to prevent its further upward travel, and is surrounded by a spring abutting against the under side of the shoulder, the lower end of the spring pressing against a nut L^2 screwed into the casing L' .

The passage N is formed in the casing A into which the train-pipe N' is screwed. A strainer n^2 is placed in the passage N and is removed and replaced by means of the plug N^3 screwed into the casing A . The passage G is formed in the casing A , leading upward and inward and terminating in the chamber C , but covered by the emergency-valve. The passage N^2 is formed in the casing A and casing L and leads from the passage N to the chamber C below the piston B . The chamber F is formed in casing A . A passage G' is formed in the casing A , one end terminating in chamber F and leading downward and inward, its other end terminating in chamber C , but covered by the emergency-valve. A passage g' is formed in the casing A with one end terminating in the lower part of chamber F , and its other end terminating in the chamber C , but covered by the emergency-valve. This passage connects with the recess d , while the emergency-valve is in normal position and making its first travel. In the chamber F is located valve F' , connected to a piston F^2 and held to its seat by air-pressure from the auxiliary reservoir, entering through the slot d^2 , passage g , recess d , and passage g' to the under side of the piston F^2 . The valve F' is seated on a seat formed on the tubular flange

f , located in the chamber F , through which flange a passage is formed. In this passage is located valve F^3 , seated against the flange, having its upper stem working in a guide formed by flange F^4 , located in the upper part of chamber E . This stem is surrounded by a spring pressing against the valve and guide. The valve is of a tubular form, the tube forming a guide for the stem of valve F' . The valve F^3 lifts when the air flows from the train-pipe to the brake-cylinder, but is held to its seat when the brake is set for service-stops by air from the auxiliary reservoir. A plate I is fixed to the upper end of the device, closing its upper end and connecting the device with the auxiliary reservoir K . In this plate is the passage C' , forming a communication between the chamber C and the auxiliary reservoir, while a passage H is formed in the plate I , forming a communication between the chamber F and passage H' , which is formed in a tube passing through the auxiliary reservoir to the brake-cylinder. The brake-cylinder is fixed to the opposite end of the auxiliary reservoir in the usual manner. The passage e^4 enters into and through plate I , terminating and connecting with the passage H . However, the relative position of the auxiliary reservoir and brake-cylinder above described may be changed if desired.

In practice or use, the parts being in their normal position, as shown in Fig. 1, and air being pumped into the train-pipe passes into chamber N and into N^2 and to chamber C and around the piston B through the by-port a to the upper part of the chamber C , thence through the passage C' to the auxiliary reservoir. The air will also pass into the slot d^3 and the passage g to the recess d , and from this recess through passage g' into chamber F below the piston F^2 , and will pass this piston, as it is not fitted to the wall of chamber F so as to be air-tight, and into the passage G' to the under side of the emergency-valve. The air will also pass through the passage e^2 into the chamber E above the piston E' . The air will also pass from the passage N into the passage G and to the under side of the emergency-valve, and from passage G to passage e and into the chamber below the piston E' , this chamber having auxiliary-reservoir air above the piston E' and train-pipe air below the piston, which will therefore be in a balanced condition, and the auxiliary-reservoir air-pressure will hold the service-valve E^3 to its seat. The piston E' is so proportioned as to the piston B that the latter will make its first travel and abut the stem M before the piston E' will unseat the service-valve.

To set the brakes a reduction is made in the train-pipe pressure and the piston B will move to the extent of its first travel and abut the stem M . This will close the by-port a and the passage or port e^5 , and upon a further reduction of the train-pipe air the piston E' will unseat the service-valve and the auxiliary-reservoir air will flow to the brake-cylinder.

through the passage e' , recess d' , and passages e^4 , H, and H' to the brake-cylinder and set the brakes. When the auxiliary-reservoir pressure has been reduced to equal the 5 train-pipe pressure, the pressure on the service-valve E^3 will cause the same to seat and the brakes will remain set. If it is desired to set the brakes with a greater pressure, a further reduction is made in the train-pipe pressure and the piston E' will again unseat the service-valve and a further flow of auxiliary-reservoir air to the brake-cylinder will occur, and this can be continued until the auxiliary-reservoir air-pressure and the brake-cylinder 10 air-pressure will be equal. Upon a restoration of the train-pipe air-pressure the piston B will move to its normal position and release the brakes. The positions of the piston B, the emergency-valve, and the service-valve 15 in the foregoing operation are shown in Fig. 5.

To set the brakes for an emergency a reduction is made in the train-pipe pressure in order to have the pressure on the piston B move it through its first travel and to overcome the 20 resistance of the spring around the stem M, and the piston will move to its fullest travel to the position shown in Fig. 9 and carry with it the emergency-valve. The recess d will connect the passages G and G' as the valve travels downward, but before connecting them it will close the passages g and g' from recess d , and as the connection of passages G and G' is made the recess d^2 will connect the passages g' and e^6 , forming an open way from chamber 25 F below the piston F^2 to the atmosphere, at which time the pressure above the piston in chamber F will move it downward, unseating the valve F' and seating the piston on a gasket located in the bottom part of chamber F, making 30 an air-tight seating. This will form a large direct passage from the train-pipe to the brake-cylinder that will quickly admit the train-pipe air to the brake-cylinder, emptying the train-pipe. In this position the emergency-valve will uncover the port e^4 and the auxiliary-reservoir air will flow to the brake-cylinder and all the brakes will set quickly. When the auxiliary-reservoir air is added to the train-pipe air in the brake-cylinder the 35 pressure in the brake-cylinder will be greater than that in the train-pipe and the valve F^3 will close. The positions of the piston B, the emergency-valve, stem M, valve F' , piston F^2 , valve F^3 , and the connections between the ports and 40 passages in this operation are shown in Fig. 9.

To release the brakes the pressure in the train-pipe is restored, whereby the piston B will travel upward, moving the emergency-valve, closing the connection between passages G and G' , and closing the passage from chamber F to the atmosphere. The passages g and g' will then be connected by the recess d and the air from the auxiliary reservoir will flow to the lower part of chamber F below 45 piston F^2 and the piston will seat the valve F' . The further travel of the piston and the emergency-valve will connect the ports e^4 and

e^6 with recess d' and release the brakes, at which time the parts will be in their normal position, as shown in Fig. 1.

The only function of the piston B and the emergency-valve in the first travel of the piston is to close the by-port a and the port or passage from the brake-cylinder to the atmosphere. The entire setting of the brakes for 50 service stops by venting auxiliary-reservoir air to the brake-cylinder is performed by the service-valve alone. Upon the full travel of the piston and emergency-valve the valve first vents the train-pipe air to the brake-cylinder 55 and next vents the auxiliary-reservoir air thereto.

The certain and positive action of the emergency-valve is assured by its being always in a balanced condition and moving at every 60 action of the brake, whereby its sticking from the accumulation of dirt or dust by reason of infrequent use (as is the case where the emergency-valve is only called into action in cases of emergency) is avoided. The balancing of 65 the emergency-valve permits it to move with a small reduction of the train-pipe pressure, and the action of the service-valve is independent of the piston and the emergency-valve, thereby assuring the certain action of 70 the emergency-valve if the service-valve should fail to act.

Although I have described more or less precise forms and details of construction, I do not intend to be understood as limiting myself thereto, as I contemplate changes in form, proportion of parts, and substitution of equivalents, as circumstances may suggest or render expedient, without departing from the spirit of my invention, and, furthermore, 75 where I have designated certain parts by their reference-letters in the specification or claims it is obvious that I do so for clearness and certainty, and not as intending to limit myself to their particular form and location 80 shown in the drawings.

I claim—

1. In a brake mechanism, the combination of a train-pipe, an auxiliary reservoir, a brake-cylinder, a slide-valve actuated by a 90 piston, the preliminary travel of the valve controlling the brake-release and its further travel admitting air from the train-pipe direct to the brake-cylinder and a service-valve for controlling the admission of air from the auxiliary reservoir to the brake-cylinder, independent of the piston of the slide-valve after the slide-valve has made its preliminary travel.

2. In a brake mechanism, the combination of a train-pipe, an auxiliary reservoir, a brake-cylinder, a service-valve controlling the admission of air from the auxiliary reservoir to the brake-cylinder and a slide-valve for controlling the brake-release and also for 95 making a direct connection between the train-pipe and brake-cylinder for emergency purposes, and means for operating the service-valve and the slide-valve independently of 100

each other, the service-valve and the slide-valve acting independently of each other when the parts are in service position.

3. In a brake mechanism, the combination of a train - pipe, an auxiliary reservoir, a brake-cylinder, a service-valve for controlling the admission of air from the auxiliary reservoir to the brake-cylinder, and an emergency device consisting of a balanced slide-valve and means for actuating the same, the slide-valve being independent in action from the service-valve, and controlling - passages from the train-pipe to the brake-cylinder.

4. In a brake mechanism, the combination of a train - pipe, an auxiliary reservoir, a brake - cylinder, a service - valve controlling auxiliary-reservoir air and a slide-valve balanced as to the ports and passages between the train-pipe and brake-cylinder, for operating the brake-release in initial traverse and governing emergency action in full traverse.

5. In a brake mechanism, the combination of a chamber or casing communicating by passages respectively with the auxiliary reservoir, brake-cylinder and train-pipe, a piston adapted to travel within the chamber, a slide-valve carried by the piston and adapted to control the brake-release port, said valve being balanced as to the ports and passages leading from the train-pipe to the brake-cylinder, a passage direct from the train-pipe to the brake-cylinder but interrupted by the slide-valve except during the full traverse and a service-valve interposed in the passage between the auxiliary reservoir and brake-cylinder and balanced by auxiliary-reservoir pressure and train-pipe pressure.

6. In a brake mechanism, the combination with a train-pipe, an auxiliary reservoir and a brake-cylinder, of a slide-valve controlling the brake-release, and provided with a chamber, a piston therein, passages respectively from the reservoir and train-pipe, and communicating on either side of the piston, said slide-valve having a passage leading from its chamber to the brake-cylinder and a valve controlling such passage and actuated by the piston.

7. In a brake mechanism, the combination of a chamber or casing communicating by passages respectively with the auxiliary reservoir, brake-cylinder and train-pipe, a piston adapted to travel within the chamber, a slide-valve actuated by the piston and adapted to control the brake-release, the slide-valve having an interior chamber with passages communicating respectively with the reservoir, train-pipe and brake-cylinder and a piston traveling in the slide-valve chamber and balanced by reservoir and train-pipe air respectively.

8. In a brake mechanism, the combination of a train-pipe, an auxiliary reservoir, a brake-cylinder, a piston traveling in a chamber, passages communicating with the auxiliary reservoir and train-pipe and leading respectively above and below the piston, a passage lead-

ing from the chamber to the brake-cylinder and closed when the pressure in the train-pipe and reservoir is equalized and the piston thereby balanced and means for releasing the brake-cylinder.

9. In a brake mechanism, the combination of a train-pipe, an auxiliary reservoir, a brake-cylinder, a valve controlling the admission of auxiliary-reservoir air to the brake-cylinder and normally balanced by reservoir and train-pipe air to close the passage to the brake-cylinder, a slide-valve controlling the brake-release in partial traverse and forming a direct communication between the train-pipe and brake-cylinder in full traverse, said slide-valve being balanced as to the ports and passages between the train-pipe and brake-cylinder.

10. In a brake mechanism, the combination of a train-pipe, an auxiliary reservoir, a brake-cylinder a valve arranged in a passage from the auxiliary reservoir to the brake-cylinder and normally closing the passage by the balancing action of auxiliary - reservoir and train-pipe air, whereby a reduction of pressure in the train-pipe will open the valve and admit air to the brake-cylinder, and a slide-valve controlling the brake-release in partial traverse and making a direct connection between the train-pipe and brake-cylinder in full traverse, said slide-valve being balanced as to the ports and passages between the train-pipe and brake-cylinder.

11. In a brake mechanism, the combination of a chamber or casing communicating with the auxiliary reservoir and a brake-cylinder, a piston traveling in such chamber, a slide-valve actuated by the piston and controlling the brake-release, a passage leading direct from the train-pipe to the brake-cylinder and having ports opening against the slide-valve by which the passage is normally interrupted, such valve having a recess d for connecting said ports at full traverse whereby the air is admitted direct from the train-pipe to the brake-cylinder for emergency purposes, a piston traveling in a chamber which is formed in the slide-valve and which communicates with the auxiliary and brake-cylinder and also with the train-pipe, the reservoir-pressure and train-pipe pressure acting on opposing faces of the piston within the slide-valve whereby the same is balanced when the pressure equalizes and a valve controlled by the piston and closing the passage to the brake-cylinder when the piston is balanced but opening the same when the train-pipe pressure is reduced and the equilibrium destroyed.

12. In a brake mechanism, the combination of a chamber or casing communicating with the auxiliary reservoir and brake-cylinder, a piston adapted to travel in such chamber, a slide-valve actuated by the piston and controlling the brake-release, a piston traveling within a chamber formed within the slide-valve, such chamber having passages in com-

munication with the reservoir, brake-cylinder and train-pipe, the reservoir and train-pipe pressure acting on opposing faces of the piston within the slide-valve whereby the same is balanced when the said pressure equalizes, the said last-named piston having a valve-body on the stem adapted to normally close the passage from the chamber within the slide-valve to the brake-cylinder but to be unseated when the train-pipe pressure is reduced.

13. In a brake mechanism, the combination of a service-valve controlling admission of reservoir-air to the brake-cylinder and an emergency-valve controlling both emergency action and the brake-release in all actions of the mechanism.

14. In a railway-brake mechanism, a slide-valve actuated by a piston, the first travel of the piston closing the communication between the train-pipe and auxiliary reservoir, and the first travel of the valve closing the communication between the brake-cylinder and the atmosphere, in combination with a valve for venting the auxiliary-reservoir air to the brake-cylinder, and independent of the piston.

15. In a railway-brake mechanism, a slide-valve for closing the communication between a brake-cylinder and the atmosphere by its initial travel, and opening a direct passage from the train-pipe to the brake-cylinder at full traverse in combination with an auxiliary valve for venting auxiliary-reservoir air to the brake-cylinder, the movement of the auxiliary valve being independent of the movement of the slide-valve.

16. In a railway-brake mechanism, the combination of a slide-valve, balanced as to the ports and passages between the train-pipe and brake-cylinder, and a piston, the initial travel of the valve closing the communication between the brake-cylinder and the atmosphere and the full travel of the valve admitting air from the train-pipe to the brake-cylinder.

17. In a railway-brake mechanism, the combination of a train-pipe, an auxiliary reservoir, a brake-cylinder and a slide-valve provided with a recess, such valve governing the ports and passages leading from the train-

pipe to the brake-cylinder and balanced as to these ports and passages, by train-pipe air in the initial port or passage G and auxiliary-reservoir air in the port G' and the recess.

18. In a brake mechanism, the combination of a train-pipe, an auxiliary reservoir, a brake-cylinder, a slide-valve having a recess, a direct passage from the train-pipe to the brake-cylinder having its course interrupted by the slide-valve but made continuous when in conjunction with the recess at certain movements of the slide-valve whereby the two passages G and G' normally open upon the face of the slide-valve, a passage d³ extending through the slide-valve and a passage g connecting passage d³ with the port or passage G' through the recess d, whereby reservoir-air presses upon the slide-valve at G' and train-pipe air at G.

19. In a brake mechanism, the combination of a train-pipe, an auxiliary reservoir, a brake-cylinder, a slide-valve provided with a recess, a passage from the train-pipe opening against the face of the slide-valve, a second passage from the face of the slide-valve to the brake-cylinder, such passages forming a direct connection between the train-pipe and brake-cylinder when connected by the recess, and a passage normally conducting reservoir-air to the said second passage whereby the slide-valve will be balanced by the train-pipe pressure and auxiliary-reservoir pressure pressing upon the same face of the valve and against the reservoir-air on the other face.

20. In a brake mechanism, a slide-valve controlling a direct passage between a train-pipe and a brake-cylinder, such valve being balanced by train-pipe pressure and auxiliary-reservoir pressure acting in conjunction on one face of the valve and against auxiliary-reservoir air acting alone on the other face.

21. In a brake mechanism, a slide-valve controlling a direct passage between a train-pipe and a brake-cylinder, such valve being balanced by auxiliary-reservoir pressure exerted on both faces.

HARVEY S. PARK.

Witnesses:

ALBERT H. LOEB,
JNO. B. GROMMES.

It is hereby certified that in Letters Patent No. 555,877, granted March 3, 1896, upon the application of Harvey S. Park, of Chicago, Illinois, for an improvement in "Fluid-Pressure Brakes," an error appears in the printed specification requiring correction as follows: In line 12, page 4, the hyphen between the words "controlling" and "passages" should be stricken out; and that the said Letters Patent should be read with this correction therein that the same may conform to the record of the case in the Patent Office.

Signed, countersigned, and sealed this 16th day of February, A. D., 1897.

[SEAL.]

JNO. M. REYNOLDS,
Assistant Secretary of the Interior.

Countersigned:

JOHN S. SEYMOUR,
Commissioner of Patents.
